FRANK E. WATTS AND DONALD T. HASTINGS, OF DETROIT, MICHIGAN, ASSIGNOR
TO HUFF MOTOR CAR COMPANY, OF DETROIT, MICHIGAN, A CORPORATION OF
MICHIGAN.

SPEEDOMETER-DRIVE FOR VEHICLES.

1,088,042.

Specification of Letters Patent.

Patented Feb. 24, 1914.

Application filed July 18, 1913. Serial No. 778,716.

To all whom it may concern:

Be it known that we, FRANK E. WATTS and DONALD T. HASTINGS, citizens of the United States of America, residing at Detroit, in the county of Wayne and State of Michigan, have invented certain new and useful Improvements in Speedometer-Drives for Vehicles, of which the following is a specification, reference being had therein to the accompanying drawings.

The invention relates to speedometer drive mechanisms of that type in which the rotation of one of the steering wheels is transmitted to the speedometer through a flexible shaft transmission. It is usual with such constructions to employ a bevel gear train intermediate the wheel and the flexible shaft, said train being mounted upon the knuckle or stub-axle on which the wheel is journaled. As this knuckle is moved with each adjustment of the wheel in steering, there is a constant flexing of the shaft which eventually results in breaking. Thus the life of the connection is comparatively short and uncertain.

It is the object of the present invention to avoid this strain upon the transmission shaft—first, by providing swivel connection which permits the turning of the knuckle without a corresponding angular movement of the shaft; and second, by preferably locating this swivel in alinement with the axis of the knuckle, thereby avoiding any movement of the shaft by the turning of the knuckle.

In the drawings: Figure 1 is a longitudinal section through the stub-axle or knuckle of the steering wheel showing our drive mechanism applied thereto; Fig. 2 is a similar view showing a modified construction; and Figs. 3 and 4 are plan views respectively of the constructions shown in Figs. 1 and 2.

A is the hub of the steering wheel; B is the stub-axle on which said hub is mounted; C is the vertical shank for the stub-axle which forms the knuckle; D is a drive shaft passing axially through the stub-axle and attached at its outer end to the hub; and E are bevel gears at the inner end of said shaft for communicating the movement therefrom to a flexible shaft F.

In the construction shown in Fig. 1, the driven bevel gear wheel E is mounted upon a shaft G, which is arranged in axial aline-

ment with the shank C of the knuckle. From this shaft motion is transmitted through bevel gear wheels H to a transversely-arranged shaft I directly coupled with the flexible shaft F. By this arrangement no movement of translation is imparted to the shaft G by the turning of the knuckle, on account of the axial alinement of these parts, while lateral movement of the shaft I is prevented by journaling the same in a bearing J, which has a swivel connection K to the knuckle. It will therefore be apparent that the turning of the steering wheel will produce no effect upon the flexible shaft F, such as is ordinarily produced in speedometer drives.

With the modified construction shown in Fig. 2, in place of arranging the shaft G in axial alinement with the shank C, the shaft D is extended through the inner end of the stub-axle B, and is then connected by bevel gear wheels F' to a shaft G', which latter is connected by bevel gear wheels H' with a shaft I' coupled to the flexible shaft F. There is also a swivel connection K' between the bearing J' for the shaft I' and the knuckle. With this construction there will be a lateral movement of the shafts G' and I' whenever the knuckle is turned, but on account of the swivel connection K', the shaft I' is free to move angularly in relation to the knuckle. This relieves the flexible shaft F from sharp bending stress which would otherwise be produced by the turning of the knuckle, and the slight movement of translation of the shafts I' and G' will be compensated for by a very slight flexing of the shaft F.

With each of the constructions as above described, the flexible shaft is greatly relieved from stress and the life of the structure is therefore prolonged.

What we claim as our invention is:

1. The combination with a stub-axle and knuckle, of a shaft extending axially through said stub-axle, a transmission shaft operatively connected with said first-mentioned shaft, and a swiveled bearing for said transmission shaft upon said knuckle permitting relative angular movement.

2. The combination with a stub-axle and a knuckle, of a shaft extending axially through said stub-axle, a transmission shaft, a gear connection between said first-mentioned shaft and transmission shaft, and a

- swiveled bearing for said transmission shaft upon said knuckle permitting relative angular movement without interference with the operation of said gearing.
5. 3. The combination with a stub-axle and a knuckle, of a shaft extending axially through said stub-axle, a shaft geared to said first-mentioned shaft, extending transversely thereto, a shaft, geared to the last-mentioned shaft extending transversely thereto and in a plane substantially parallel to that of the said first-mentioned shaft, and a bearing for the last-mentioned shaft swiveled concentric with the intermediate shaft.
10. 4. The combination with a stub-axle and a knuckle, of a shaft extending axially therethrough, a shaft extending transversely to said first-mentioned shaft in axial alignment with said knuckle, a shaft driven from said last-mentioned shaft, and a bearing therefor swiveled concentric with the intermediate shaft.
15. 5. The combination with a stub-axle and a knuckle, of a shaft extending axially through said stub-axle, a shaft extending transversely of and geared to said shafts to form a transmission connection therebetween, and a swivel for the driven shaft in relation to said knuckle.
20. 6. The combination with a stub-axle and a knuckle of a shaft passing axially through said stub-axle, a transversely-extending shaft, bevel gears connecting said shafts, a shaft extending transversely to the last-mentioned shaft and driven therefrom, and a swiveled bearing for said last-mentioned shaft upon said knuckle.

In testimony whereof we affix our signatures in presence of two witnesses.

FRANK E. WATTS.

DONALD T. HASTINGS.
